UNITED STATES PATENT OFFICE

ALLEN A. HORTON, OF PLYMOUTH, MICHIGAN, ASSIGNOR TO BURROUGHS ADDING MACHINE COMPANY, OF DETROIT, MICHIGAN, A CORPORATION OF MICHIGAN

CALCULATING MACHINE

Original application filed January 29, 1926, Serial No. 84,616. Divided and this application filed August 6, 1926. Serial No. 127,509.

This invention relates to a calculating machine particularly one that will both add and subtract.

In my co-pending application, Serial No. 84,616, filed January 29, 1926, of which the present case is a division, I have shown a calculating machine that may be conditioned for either addition or subtraction and the present invention concerns said machine, especially the mechanism by means of which addition and subtraction may be performed on the same counter with the same transfer mechanism acting to either carry or borrow.

Although the invention is illustrated with said machine it is not necessarily limited to it as will later appear.

The general object of the invention is to provide an improved calculating machine that will both add and subtract on the same counter with a single, simple transfer mechanism acting to both carry and borrow on said counter.

A more particular object is to provide an improved transfer mechanism for calculating machines.

Other objects and advantages of the invention will hereinafter appear.

An embodiment of the invention is illustrated in the accompanying drawings in which:

Fig. 1 is a side elevation of my calculating machine showing some of the controlling mechanism therefor.

Fig. 2 is a side elevation of the rear end of the calculating machine with the side plate removed to show some of the interior mechanism.

Fig. 3 is a spread perspective view of a section of the transfer mechanism.

Fig. 4 is a section on the line 4—4 of Fig. 2.

Fig. 5 is a side elevation of the transfer mechanism showing the counter in engagement with the actuator racks and the transfer mechanism in a position prior to a carry being effected.

Fig. 6 is a side elevation similar to Fig. 5 showing the position of the parts when an "initial carry" has been effected.

Fig. 7 is a side elevation similar to Fig. 5 showing the counter out of engagement with

the racks and the parts in the condition they occupy after a full carry has been effected.

Fig. 8 is a side elevation similar to Fig. 5 showing the transfer mechanism in condition for borrowing and the parts in the position they occupy as an initial carry is being completed.

Fig. 9 is a view similar to Fig. 8 with the counter out of engagement with the racks and the parts in the position they occupy after a carry has been effected.

Fig. 10 is a side elevation of the control mechanism showing the parts in the position they occupy when set so that operation of the machine will automatically condition the transfer mechanism to borrow instead of carry.

Fig. 11 is a fragmentary view similar to Fig. 10 showing the parts in the position they occupy after the transfer mechanism has been moved to subtraction or "borrow" position.

The construction and operation of the calculating machine has been described in detail in my co-pending application referred to and will be described only briefly here. Insofar as possible the same reference numerals will be used to designate similar parts in the two applications.

The machine is provided with a plurality of banks of depressible amount keys 10 shown in Fig. 2, having stems 11 which project through the keyboard and are adapted to be positioned in the path of differentially located stops 252 on the stop bars 233. There is one of these stop bars for each bank of amount keys, their forward ends being slidably mounted and their rear ends being connected to the vertical arms 234 of actuator segments 235, which operate the totalizer or counter pinions. The stop bars are normally urged forward by springs 250 which thereby also normally urge the actuator racks counter-clockwise. These parts are held against movement by the cross bar 255 of a bail 256, which is normally urged in a counter-clockwise direction by the spring 258. The bail is prevented from moving in a counter-clockwise direction by the engagement of a cam roller 260 carried by it with the

cam surface of a cam 73 which is rocked by the main shaft 71 of the machine (Fig. 1). When the handle is pulled forward the cam 73 is rocked to present a surface of the cam 5 to the roller 260 which will permit the roller with its bail to move counter-clockwise and release the actuator racks which thereupon move counter-clockwise to differential positions determined by the engagement of the 10 stops 252 on the stop bars 233 with the stems of the depressed amount keys. Each actuator rack carries a type bar 264 that is properly positioned at the printing line as the actuators move to differential positions. 15 Upon the return stroke of the machine the bail 255 is moved clockwise to restore all the actuator racks to their normal position. When addition is to be performed the counter, which comprises a plurality of pinions 20 236 adapted to mesh with the actuator racks 235, is moved into engagement with the racks at the end of the forward stroke of the machine, so that when the bail restores the racks to normal position, the pinions are moved distances corresponding to the differential positions of the actuators. At the end of the 25 return stroke the counter is moved out of engagement with the racks and the amount set up is thus stored in the counter. 30 When a total is to be taken from the counter, the latter is moved into engagement with the racks at the beginning of the forward stroke and prior to the ascent of the racks. The counter pinions are provided with stops 35 which stop them at zero when they are rotated backward. As the racks ascend in taking a total the counter pinions are rotated to zero and the position of the racks is thereby determined. This also positions the type 40 bars so that the total can be printed. At the end of the forward stroke and while the counter is "clear" or at zero position, it is moved out of engagement with the racks and it so remains during their restoration to normal position. The same action takes place 45 in taking a subtotal except that the nose 400 of pawl 399 is not moved to active position and the counter remains in engagement with the racks during both their ascent and their 50 descent. When the total or subtotal key is depressed a lever 358 is raised through suitable connections into the path of the cranked end of a shaft 446 to thereby block the counter pinions so that they will stop at zero 55 when rotated backward by the ascent of the racks. The pinions thus determine the position of the racks in the taking of a total. When subtraction is to be performed the counter pinions are moved into engagement 60 with the actuator racks at the beginning of the forward stroke of the machine and prior to their ascent the same as in taking a total but instead of the counter pinions being blocked at zero position they are free to move 65 past the "0" position and the differential po-

sitions of the racks with their type bars are determined by the engagement of the stop bars with the amount keys. During the forward stroke and as the actuators are released, the counter pinions are moved in the reverse direction to that in which they were rotated for addition and the amount set up in the machine is subtracted from the counter, which is moved out of engagement with the racks at the end of the forward stroke. 70

Suitable transfer mechanism must be provided for carrying a unit from a pinion of lower to a pinion of higher order when the lower order pinion has rotated a full revolution or from the "9" to its "0" position. Various mechanisms have heretofore been devised for this purpose but these mechanisms are peculiarly adapted to transfer only when the counter is being rotated in a direction to perform addition and are not operable to borrow or transfer in the reverse direction if the counter should be reversely rotated. Usually a separate set of pinions is employed for performing subtraction and a separate transfer mechanism is provided for this additional set of pinions or if a single transfer mechanism is employed, it operates in the same direction as the two sets of pinions as, for example, in Rinsche Patent No. 1,172,484, February 22, 1916, but is not suitable for both carrying and borrowing on one set of pinions. In the present invention, however, a single set of pinions is used for both addition and subtraction and one transfer mechanism is employed for both carrying and borrowing with provision for automatically conditioning it to perform either of these operations as the machine is conditioned to perform addition or subtraction. 95

The counter comprises a plurality of pinions 236 rotatably mounted on a shaft 376 carried by the side arms 377 connected to the rock shaft 378 pivoted in the side plates 55. The shaft 378 upon which the side arms of the counter frame are mounted also has fixed to it an arm 380 (Fig. 3) carrying a cam roller 381 adapted to be engaged by the edge of a cam plate 382 forming one side of a yoke shaped member 384 fixed to a rock shaft 383 pivoted in the side plates 55. A pitman 387 is connected to the lower side of the cam plate 382 as illustrated in Fig. 3. From Fig. 10 it will be clear that when the pitman 387 is moved rearwardly the plate 382 will be moved counter-clockwise to cam the counter into engagement with the racks and when the pitman 387 is pulled forwardly the plate 382 will be rocked clockwise to permit the counter to be moved out of engagement with the racks by the spring 385 (Fig. 3). 110

As above set forth, the counter is rocked into and out of mesh with the actuators by means of the pitman 387 (Fig. 1) pivoted at its rear end to the rocking cam plate 382 and having its forward end forked and provided 120

with devices for actuation by the drive shaft and associated parts. The pitman is reciprocated by a cam 74 rocked by the main drive shaft 71 and carrying studs 200 and 395 for 5 engagement with pawls carried by the pitman.

The normal position of the parts is shown in Fig. 1. When the machine is given a forward stroke, the cam plate 74 is rocked counter-clockwise and during this movement the studs 200 and 395 do not act on the pitman. As the end of the forward stroke is reached, the stud 395 passes a pass-by pawl 393 pivoted to the upper arm of the pitman and held 15 in position by a spring 394 so that, at the beginning of the return stroke, the stud engages the shoulder 396 of said pawl and moves the pitman rearwardly to move the counter into engagement with the racks. 20 Near the end of the return stroke the stud 200 engages the nose 391 on the lower arm of the pitman and returns it forwardly to rock the counter out of engagement with the racks. This is the normal action of the pitman for addition. 25

When a total is to be taken the total key T is depressed (Fig. 1) which rocks a pivoted member 367 downwardly in a counter-clockwise direction. This member is connected 30 by means of a connection 406 to a pawl 404 pivoted on the lower arm of the pitman 387 and the downward movement of the member serves, by means of this connection, to move the pawl 404 into the path of the stud 200. The member 367 contacts a pawl 399 pivoted to the upper branch of the pitman and when the member 367 is moved downwardly by the total key the pawl 399 is moved down to a position such that its nose 40 is in the path of the stud 395. The pawl 399 has a central projection 401 which contacts the tail of the pawl 393 to move it to inactive position when the pawl 399 is moved downwardly by depression of the total key. 45 Accordingly, when the machine is given a forward stroke under these conditions, the stud 200 engages the pawl 404 and moves the pitman 387 rearwardly at the beginning of the forward stroke to thereby move the 50 counter into engagement with the racks at the beginning of the forward stroke. At the end of the forward stroke, the stud 395 engages the hook 400 of pawl 399 and pulls the pitman 387 forwardly to disengage the 55 counter from the racks. During the return movement of the cam plate 74 the stud 395 has no effect on the pitman as the pawl 393 is held out of active position by the projection 401 and since the pitman is already in its forward position there is no movement caused by stud 200 contacting the nose 391 of the lower branch of the pitman.

When subtraction is to be performed, the subtraction lever 226 is moved from the position of Fig. 1 to that of Fig. 10. This lever

is connected by a link 363 to a yoke-shaped arm 362 having a portion contacting the tail of the member 367 so that, as the subtraction lever is moved rearwardly, the arm 367 is rocked downwardly to the position of Fig. 70 10. This action moves the pawl 404 into the path of the stud 200 by means of the connection 406. The pawl 399 is also moved down to position its hooked end 400 in the path of the stud 395 and to cause its central projection 401 to contact the tail of pawl 393 to move the latter to inactive position. Accordingly, at the beginning of the forward stroke, the stud 200 engages the pawl 404 to move the pitman 387 rearwardly to rock the counter into engagement with the racks where it remains until near the end of the forward stroke when the stud 395 engages the hooked end 400 of pawl 399 and pulls the pitman 387 forward to rock the counter out of engagement with the racks. During the return movement the stud 395 passes the pawl 393 which is held out of active position and the stud 200 passes by the pawl 404, neither of said studs acting to move the pitman upon 80 85 90 95 100 the return stroke.

The transfer mechanism includes a plurality of toothed transfer segments 413 pivoted on a shaft 414 carried by the side plates 55, there being one transfer segment for each counter pinion. In order to avoid confusion the description will be directed primarily to the transfer devices for one pinion, it being understood that there is a similar device for each pinion. 105

The transfer segment 413 is normally held in the position shown in Fig. 5 by the engagement of a lateral lug 416^a on its upwardly extending arm 416 in a notch in the bell crank detent 420 which is urged in a clockwise direction by the spring 420^a. The bell crank detent 420 is controlled by a pinion of next lower order than the one with which the transfer segment engages as will be clear from Fig. 3. The downwardly extending arm 420^b of the detent extends behind a pivoted tripping pawl 422 having a tooth-like projection 423 adapted to be engaged by a wide tooth 433 on the pinion 236. The tripping pawl is pivoted on a shaft 423 carried by the side arms 377 of the counter frame so that the pawl moves with the counter as it is rocked into and out of engagement with the racks, and it is urged in a counter-clockwise direction by a spring 428, one end of which is connected to the tail of the pawl, and the other end of which is connected to a latch 426 pivoted on the shaft 427 also carried by the side arms 377 of the counter frame. A lateral projection 424 is formed on the pawl 422 for engagement with a shoulder 425 on the latch 426 which latches the pawl in retracted position under certain conditions hereinafter explained. 110 115 120 125

For purposes of carrying when the ma- 130

chine is performing addition the transfer segments are normally urged in a clockwise direction by springs 417 connected at one end to the arms 416 of the segments and at 5 their other ends to a rod 417^a carried by the cross bar 418^a of a pivoted bail 418.

A restoring bail for the segments is provided comprising a cross shaft 430 carried by arms 429 movable with the rocking yoke 384. 10 This bail moves up and down in slots 431 in the side plates 55 (Fig. 1) and between the downwardly extending arms 415 of the transfer segment from the position between the narrow opening between said arms to the 15 wider opening between them. As it moves down it engages the rear arm 415 of the segment and cams it counter-clockwise to normal position, the parts being proportioned so that the segment is moved sufficiently to insure 20 that the detent 420 will catch on the lug 416^a.

The operation of the transfer mechanism for carrying when the machine is performing addition is as follows:

The normal position of the parts with the 25 counter in engagement with the racks and the transfer mechanism in position before any carry has been effected is illustrated in Fig. 5. When one of the pinions is rotated from its "9" position illustrated in Fig. 5 to its 30 "0" position shown in Fig. 6, the wide tooth 433 on the pinion engages the projections 423 on the tripping pawl 422 and cams it rearwardly to the position of Fig. 6 where the pawl is latched in place by the latch 426 35 which snaps downwardly to move the shoulder 425 in front of the lug 424. This action is what is called an "initial carry".

Important features are that the tripping pawls are firmly latched in initial carry position so that they are not disturbed by jarring of the machine and that the initial carry for each pinion is individual, that is, it is not dependent on a restraining member common to all the pawls. Each pawl is operated and latched individually.

In the initial carry position the rear side of the tripping pawl 422 is in engagement with the downwardly projecting arm 420^b of the detent 420 as shown in Fig. 6. When the 50 counter is moved rearwardly out of engagement with the racks to the position of Fig. 7 it carries the tripping pawl 422 with it and the rear side of this pawl, engaging the arm 420^b, moves the detent 420 counter-clockwise and releases the transfer segment 413 which thereupon is moved by the spring 417 a distance sufficient to move the pinion that engages it one tooth. In this manner the transfer mechanism is released for operation 55 by the movement of the counter into engagement with the transfer mechanism. In moving the counter rearwardly the pitman 387 is pulled forward which rocks the cam plate 382 clockwise and raises the restoring bail 430 upwardly to the position illustrated in

Fig. 7 in the wide space between the arms 415 of the transfer segment which permits the segment to turn on its pivot without interference from the restoring bail. The bail is raised prior to the moving of the segments 70 by reason of the fact that, as the cam plate 382 moves counter-clockwise toward its Fig. 3 position, the roller 381 rides on the raised portion of the cam and the totalizer cannot move rearwardly to trip the carry segments. 75 During this movement of the cam plate the bail 430 is rising and it reaches the position shown in Fig. 7 at about the time the roller 381 reaches the depressed part of the cam plate. This bail also acts as a limit stop 80 for the segment to limit its movement to an amount just sufficient to move its pinion one tooth. As the bail rises, it contacts the ends of all the latches 426 and raises them out of engagement with the lugs 424 on the tripping pawls 422, whereupon these pawls are restored to normal position by the springs 428. When the bail is lowered again the latches ride on the lugs 424 in the position illustrated in Fig. 5. 85

The transfer mechanism is restored to normal as the counter is moved into engagement with the racks. As this movement occurs the bail 430 is lowered and it engages the rear arms 415 of the transfer segments to cam them counter-clockwise to restore all of the tripped segments to normal after the pinions have been moved out of engagement with the segments. The segments are then latched in position by the detents 420, the 100 notches of which snap over the lateral lugs 416^a on the segments. The parts then occupy the position shown in Fig. 5.

In taking a total the total key T is depressed, which rocks the lever 358 counter-clockwise to move its end in front of the cranked end 446 of a shaft 447 pivoted in side arms 377 of the counter frame. A locking plate 448 is fixed to the shaft 447 and the latter is normally urged clockwise by a spring 450 which maintains the locking plate in a substantially horizontal position as shown in Fig. 5. When the counter is rocked into engagement with the racks in the taking of a total, the engagement of the crank 446 with the end of lever 358 turns the shaft 447 on its axis counter-clockwise and rocks the plate 448 behind the projections 422^a on the tripping pawls 422. This prevents the pawls from moving rearwardly and hence when the pinions are rotated backward in the ascent of the racks, they are stopped in "0" position when the broad tooth 433 on each engages the upper face of its tooth 423 on its tripping pawl. 115

An important advantage of the invention is that it is not necessary to give the machine a spacing stroke prior to taking a total. The transfer segments are restored to normal whenever the counter is moved into engage- 125

ment with the racks. If a number of items have been accumulated and a total is taken, the movement of the counter into engagement with the racks at the beginning of the forward stroke of the machine restores all the tripped carry segments because the bail 430 is lowered to restore the segments simultaneously with the moving of the counter into engagement with the racks.

10 In taking a subtotal, the action is the same as in taking a total except that the counter is not moved out of engagement with the racks at the end of the forward stroke.

When subtraction is performed, the counter pinions are rotated in the opposite direction to that in which they are rotated for addition and the transfer mechanism must effect borrowing from a pinion of higher order to one of lower order, that is, the action is the reverse of what it is in addition.

Each of the broad teeth 423 on the tripping pawls 422 is shaped so that it will cam its pawl rearwardly when the pinion is moving in either direction. In other words, the 25 pawls are not only cammed rearwardly when the pinions move from "9" to "0", but also when they move from "0" to "9". Accordingly, the transfer mechanism is set for the initial carry in subtraction in the same manner as in addition. The carry is also completed in the same general way,—that is, when the counter is moved out of engagement with the racks, the tripping pawls 422 move the detents 420 to release the transfer segments. However, in order to effect a borrow, it is necessary that the transfer segments move in the opposite direction to which they move for effecting a carry. This reversal of movement is achieved in the present 35 invention by changing the effective direction of the action of the springs 417. The pivoted bail 418 is swung from the position shown in Fig. 5 to that shown in Fig. 8 so that when the transfer segments are released, the springs move them counter-clockwise instead of clockwise as they are moved when the parts are in the condition shown in Fig. 5. Accordingly, when the transfer segments are released, those that have been 45 tripped are moved to borrow a unit from a pinion of higher order for a pinion of lower order. Fig. 8 shows the position of the parts after an "initial borrow" has been completed in subtraction. The position of the parts 50 when the borrow is completed is illustrated in Fig. 9 where the transfer segment has been moved by the spring 417, the restoring bail 430 having moved up to permit a movement of the segment equal to one tooth on the counter pinion. The segments are restored to normal position by the bail 430 in the same general manner as heretofore described and it will be noted that the one bail serves to limit the movement of the segments to one 55 tooth distance in both directions, to restore

the segments to normal position from both the carry and the borrow positions, and to raise the latches 426 to permit the tripping pawls to move back to normal.

The automatic conditioning of the transfer mechanism for carrying or borrowing is accomplished through connections from the subtraction lever 226. This lever is connected by a link 363 to a bell crank lever 362 having a rearwardly extending arm 362^a whose bifurcated end engages over a stud 439^c on a pivoted arm 439^b whose lower end is connected to one end of a spring 437^b, the other end of the spring being connected to an arm of a pivoted cam plate 436^b. When the machine is in condition for addition, the parts occupy the position illustrated in Fig. 1.

When the machine is conditioned for subtraction, the lever 226 is moved rearwardly which rocks the bell crank 362 counter-clockwise and moves the lever 439^b clockwise to the position illustrated in Fig. 10. This moves the spring 437^b across the pivot of the cam plate so that the spring then moves the plate counter-clockwise to the position of Fig. 10 where its shoulder 436^c is in front of a stud 440 carried by the cam plate 382 connected to the reciprocating pitman 387. Accordingly, when the pitman 387 is moved rearwardly at the beginning of the forward stroke of the machine and the plate 382 is rocked counter-clockwise, the stud 440 engages the shoulder 436^c and moves the cam plate 436^b with it. The cam plate 436^b is pivoted to an arm 435 having a slotted end engaging over a stud 434 on the end of the bail 418. When the cam plate 436^b is moved forward with the plate 382 the bail 418 is rocked from the position of Fig. 5 to that of Fig. 8 thereby conditioning the transfer mechanism to effect a borrow instead of a carry. This action takes place automatically as the machine is operated after being conditioned for subtraction.

When the machine is conditioned for addition after having been used for subtraction, the subtraction lever 226 is pulled forwardly which rocks the bell crank lever 362 in a clockwise direction, thereby moving the lever 439^b from the position of Fig. 10 to that of Fig. 1. This moves the spring 437^b across the pivot of the cam plate 436^b which thereupon is moved from the position of Fig. 10 to that of Fig. 1 by the spring. The hook-shaped end 436^d of the cam is then in front of a stud 443 carried by the pivot of pitman 387 and as the pitman is moved rearwardly to throw the counter into engagement with the racks this stud engages the hooked end of the cam and moves it together with the pivoted lever 435 from the position of Fig. 11 to that of Fig. 1 which automatically conditions the transfer mechanism to effect a carry instead of a borrow.

In this manner the same set of counter

pinions is used for both addition and subtraction and the same simple transfer mechanism is used to effect both a borrow and a carry, the parts being automatically conditioned to achieve this result by the simple movement of a lever 226 from one position to another and the subsequent operation of the machine. The transfer mechanism is simple, no minutely machined parts are necessary, each counter pinion controls its own transfer devices, no spacing stroke is necessary, and the mechanism is returned to normal by a single bail from both its carry or its borrow positions.

15 It is to be understood that the structure shown is for purposes of illustration only and that variations may be made without departing from the spirit and scope of the invention as defined by the appended claims.

20 I claim:

1. A calculating machine having actuator racks, a frame carrying a plurality of counter pinions having transfer projections, said frame being pivoted adjacent said racks so 25 that it may be rocked to rock said counter into and out of engagement with said racks, trip pawls pivoted on said frame to swing about an axis substantially parallel to the axis of said frame, said pawls having projections positioned for engagement by said transfer projections when the pinions pass from their "9" to or through their "0" positions and vice versa whereby said pawls are moved to "initial transfer" position, latches 30 pivoted on said frame for holding said pawls in "initial transfer" position after they are moved to said position, pivoted transfer segments positioned adjacent said pinions on the side opposite said actuator racks, means 35 urging said segments in a direction to effect a transfer, latches normally restraining said segments, said transfer segment latches having portions positioned for engagement by said latched trip pawls when said counter 40 frame is moved to rock said pinions out of engagement with said actuator racks whereby said transfer segment latches are released, and a restoring bail for restoring said transfer segments.

50 2. A calculating machine having actuator racks, a frame carrying a plurality of counter pinions having transfer projections, said frame being pivoted adjacent said actuator racks so that it may be rocked to rock said 55 counter into and out of engagement with said racks, trip pawls pivoted on said frame to swing about an axis substantially parallel to the axis of said frame, said pawls having projections positioned for engagement by said transfer projections when the pinions pass from their "9" to or through their "0" 60 positions and vice versa whereby said pawls are moved to "initial transfer" position, latches pivoted on said frame for holding 65 said pawls in "initial transfer" position after

they are moved to said position, pivoted transfer segments positioned adjacent said pinions on the side opposite said actuator racks, means urging said segments in a direction to effect a transfer, latches engaging 70 the upper ends of said segments for normally restraining them against movement, said latches having portions positioned for engagement by said latched trip pawls when the counter frame is moved to rock the pinions out of engagement with the actuator racks to thereby release said transfer segment latches, and a restoring bail adapted to engage the lower ends of said transfer segments to restore them to normal, said 75 latches for said trip pawls having portions positioned for engagement by said restoring bail whereby said latches are released.

3. A calculating machine having actuator racks, a frame carrying a plurality of counter pinions having transfer projections, said frame being pivoted adjacent said racks so that it may be rocked to move the counter into and out of engagement with said actuator racks, trip pawls pivoted on said frame 80 to swing about an axis substantially parallel to the axis of said frame, said pawls having projections positioned for engagement by said transfer projections when said pinions pass from their "9" to or through their "0" 85 positions and vice versa whereby said pawls are moved to "initial transfer" position, latches pivoted on said frame and extending toward said segments for holding said pawls in "initial transfer" position after they are 90 moved by said transfer projections, pivoted transfer segments positioned adjacent said pinions on the side opposite said actuator racks, means urging said segments in a direction to effect a transfer, bell crank latches 95 for restraining said segments, one arm of said bell crank latches being adapted to engage said segments and the other arm being positioned for engagement by said latched trip pawls when said counter frame is rocked 100 to move the pinions out of engagement with the actuator racks, converging arms on the lower portions of said transfer segments, and a restoring bail between said converging 105 arms for restoring said segments, said trip-pawl latches having portions extending to a position for enabling said latches to be released by said bail.

4. The combination in a calculating machine having a counter comprising a plurality of counter pinions, of a transfer mechanism having a plurality of sets of transfer devices, each set comprising a transfer element for one pinion urged in a direction to effect a transfer, a detent for normally restraining said element, a tripping pawl movable to initial carry position by a counter pinion of another order, a latch for holding said pawl in said position, said pawl serving, when in initial carry position, to trip said de- 115 120 125

tent when the counter is brought into engagement with the transfer mechanism, and a restoring bail for restoring the transfer elements, said bail also serving to trip the latches of the tripping pawls.

5. The combination in a calculating machine having a series of actuator racks and a counter comprising a series of counter pinions carried by a frame which is movable to 10 move the counter into and out of engagement with the racks, of a transfer mechanism having a plurality of sets of transfer devices, each set comprising a tripping pawl carried by the frame and adapted to be set in initial 15 carry position by movement of its counter pinion in either direction, a latch for holding said pawl in initial carry position, a transfer segment for the counter pinion of next highest order, said segment being mounted 20 independently of the frame and being movable in two directions, actuating means for the segment, means for changing the direction of action of said actuating means, and a detent for normally restraining the 25 segment against movement in either direction, said pawl being positioned so that when it has been set in initial carry position and when the counter is moved out of engagement with the racks and into engagement 30 with the transfer segments, it will trip the detent for the transfer segment of the pinion of next high order to permit said segment to move to effect a transfer.

6. In a transfer mechanism, a pivoted 35 transfer member movable in one direction from a normal position to effect a carry and in the opposite direction to effect a borrow, said transfer member having spaced arms which converge toward one another and the 40 converged ends of which are spaced from one another, a movable restoring member between said arms, and means for moving said restoring member toward the converged ends of said arms to restore said transfer member 45 to normal from either of its moved positions, said restoring member after restoring said transfer member being positioned between the spaced ends of said arms to prevent movement of the transfer member until the 50 restoring member has been moved from between spaced ends of said arms.

In testimony whereof I have subscribed my name.

ALLEN A. HORTON.
